UNITED STATES PATENT OFFICE.

ELIHU B. HAYES, OF LYNN, MASSACHUSETTS.

TICKET-PUNCH.

SPECIFICATION forming part of Letters Patent No. 314,241, dated March 24, 1885.

Application filed January 12, 1885. (No model.)

To all whom it may concern:

Be it known that I, ELIHU B. HAYES, of Lynn, county of Essex, State of Massachusetts, have invented an Improvement in Ticket-
5 Punches, of which the following description, in connection with the accompanying drawings, is a specification, like letters on the drawings representing like parts.

In this my improved ticket-punch one of the jaws is provided with a disk or die plate, which may be rotated thereon and be retained or locked in given positions therewith, the said die-plate being provided with two male dies of different form, and preferably secured to the plate at opposite sides of its center or axis, while to the other jaw is retained a pivoted die-plate having two female dies of different form, but corresponding in shape to the male die. The purpose of such construction is to enable the die-plates to be moved on their axis to bring the desired male and its corresponding female die to the outer portion of the jaws for use in punching tickets, whereby a die of one form may be used to punch tickets during an outward trip, for instance, while, after a manipulation of the die-plates, the other die, of different form, may be employed on the return trip. Further, the jaw having the plate with female dies is slotted in the line of the outermost female die, and is provided at its outer or under side with a receptacle to receive the clippings of the tickets. Further, in my invention the male dies are set at an angle other than a right angle to its jaw or to the plane of movement of its die-plate, so that when the jaws are brought together the male die, which for the time being is brought into use for punching, enters the female die while perpendicular thereto.

40 The invention is more fully set forth in the following description, and particularly pointed out in the claims.

Figure 1 shows a ticket-punch embodying my invention; Fig. 2, a central vertical section thereof, with the levers or handles broken away. Fig. 3 shows the male die-plate in elevation and in plan, and Fig. 4 shows the female die-plate.

50 The jaws A are pivoted at a' and provided with the handles a, b , the spring a^2 , to throw the jaws apart, and the usual spring, a^3 , to strip

the ticket or other thing punched from the male die.

The upper jaw, A, is recessed on its under or inner surface to receive the disk or die-plate c , while the pivot or stud c' of said die-plate passes through the jaw A and is retained in place by means of a pin, c^2 , passing transversely through said jaw so as to enter the annular groove c^3 in the stud, whereby the die-plate is capable of being moved, on its stud while being securely retained in said jaw. A catch, d , is pivoted in the end of the jaw A, and actuated in one direction by the coiled spring d' , arranged in the socket D at the end 65 of the jaw A, as shown. The toe of the spring-actuated catch d projects into one of the two notches e , cut in opposite sides of the die-plate c , to lock the said die-plate to its jaw in one of two positions, so that either the male die 2 or the male die 3, of different form than that of die 2, may be retained in position near the outer end of the jaw, as desired. The male dies 2 and 3 are set in the die-plate c , so as to diverge from each other or project in opposite 70 directions from the die-plate, as clearly shown, whereby the operative die for the time being, as 2, enters the corresponding female die at a perpendicular thereto when the jaws are moved toward each other.

80 The lower jaw, B, is recessed and provided with a die-plate, g , having a pivot-stud, g' , retained in the jaw by the pin g^2 , passing transversely through said jaw, so as to enter the annular groove g^3 in said stud g' . The die-plate g is provided with two female dies, 4 and 5, respectively corresponding in shape to the male dies 2 and 3, to receive the same, while the said die-plate g is further provided with notches f on opposite sides thereof. The head of the bolt h engages the notches f one at a time to lock the lower die-plate, g , in one of two positions to the jaw and retain the desired female die at the outer part of the jaw B, the said bolt passing through the jaw and being provided 90 with a nut, h' , and coiled spring h^2 , as shown. The nut projects from the enlargement or extension x of the lower jaw, to permit the bolt to be forced partially through said jaw against the tension of the spring h^2 and cause the head 95 of the bolt to be moved out of the notch in the die-plate g , whereupon the said die-plate may

be given a half-turn on its pivot-stud to reverse the position of the female die.

The lower jaw, B, is provided with a slot, *k*, in the line of the female die 4, so as to permit the clippings from tickets, &c., to drop into the box or receptacle *m*, removably retained in the jaw B by means of flanges or inwardly-turned upper sides of the box (not shown) entering the grooves *n*, cut in the sides 10 of said jaw B, as clearly shown in Fig. 1.

To reverse the relative positions of the male dies 2 and 3, the spring-actuated catch *d* is moved on its pivot in toward the body of the jaw A, to withdraw the toe from the notch *e*, when the die-plate *c* may be readily given a 15 half-turn on its pivot-stud *c'*, and the catch released to lock the die-plate in its new relation by engaging the notch *e* so brought next to said catch.

20 The relative positions of the female dies may also be reversed by forcing the spring-actuated bolt *h* partially through the jaw B from the outside, to disengage the head of said bolt from the contiguous notch in the die-plate *g*. 25 When said plate is free to be turned and locked in its new position.

I claim—

1. In a ticket-punch, the jaw A, the die-plate *c*, provided at its back with the pin *c'*, and the two male dies, 2 and 3, projecting from the 30 face of the said plate, and the jaw B and the die-plate having two female dies, combined with the box *m*, all constructed and arranged substantially as described.

2. The combination, with the jaw of a ticket-punch provided with a movable die-plate having notches in its periphery, of a bolt passing through the jaw and provided with a nut and coiled spring, substantially as set forth. 35

3. In a punch, the jaw A and an attached 40 plate, provided with a male die extended from the plate at an angle with relation to the part of the jaw on which the plate rests, combined with the jaw B and its attached female die-plate and box *m*, substantially as described. 45

In testimony whereof I have signed my name to this specification in the presence of two subscribing witnesses.

ELIHU B. HAYES.
